UNITED STATES PATENT OFFICE.

JOSEPH GOULBOURN, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-SUPPORT FOR SHOE MACHINERY.

1,262,778.

Specification of Letters Patent. Patented Apr. 16, 1918.

Application filed September 1, 1914. Serial No. 859,629.

To all whom it may concern:

Be it known that I, JOSEPH GOULBOURN, a subject of the King of England, residing at Leicester, Leicestershire, England, have 5 invented certain Improvements in Work-Supports for Shoe Machinery, of which the following description, in connection with the accompanying drawings, is a specification, like reference characters on the drawings 10 indicating like parts in the several figures.

This invention relates to work supports for use in shoe machinery, and more particularly to machines of the type in which a 15 work support is arranged to be canted to allow the work to be placed thereon and then returned to normal position to bring the work into the proper relation with the operative tools of the machine. Of such 20 machines, a machine for attaching heels to boots and shoes forms a typical example. In machines of this type there is frequently employed a jack hinged so that it can be swung forwardly and canted to facilitate 25 the fitting thereon of a boot or shoe, the jack being thereafter returned to bring the heel seat of the shoe into alinement with the heel. When this relation has been established the two parts of the work are pressed 30 together and then the heel is secured to the sole by nails driven in the usual manner. In machines of this construction it sometimes happens that, if the heel seat is not quite level, there is developed a tendency to 35 cant the work support, when the pressure is exerted, with the result that the nails are improperly driven or that the heel shifts in relation to the shoe and is not secured in proper position.

40 With these conditions in view it is an object of the present invention to provide a work support which shall possess all the benefit of the canting movement for the easy reception and fitting of the work, and which 45 shall be so constructed and arranged as to obviate the possibility of canting under pressure.

With this end in view an important feature of the invention consists broadly in a 50 swinging or canting jack arranged for use as one of two coöoperating work pressing members and being provided with means for automatically locking said jack when re-

turned from its canted into its operative position.

55

As herein shown the jack is pivoted to a sliding support that by movement in one direction brings the jack, or a part thereof, into contact with a stop by which it is held from canting movement, and by movement 60 in another direction removes the jack from engagement with such stop, leaving the jack free to be canted. The bodily sliding movement of the jack is advantageous in that it takes the jack out of alinement with the opposed work engaging member when the jack is moved into work receiving position and so affords clearance for putting work on or taking it off the jack.

65

Another feature of the invention consists 70 in so constructing the stop for the jack as to allow the latter to be drawn forwardly and canted by a single movement preparatory to receiving the work and also to be returned to operative position by another single movement to position the work.

75

These and other features of the invention will be best understood and appreciated 80 from the following description of a preferred embodiment thereof selected for purposes of illustration and shown in the accompanying drawings, in which,—

85

Figure 1 is a view in side elevation of the jack and its associated parts in operative position;

85

Fig. 2 is a similar view showing the jack in its canted or work receiving position; and

90

Fig. 3 is a front view partly in section of the parts shown in Fig. 1.

95

The accompanying drawings illustrate the present invention as embodied in a heel attaching machine of the type disclosed in Letters Patent of the United States, No. 1,195,134, granted Aug. 15, 1916, on my application Serial No. 722,270, filed September 25, 1912, although it is to be understood that the invention is not limited to this or any other particular type of machine, but has a general application. In the present 100 machine, as in the machine of said application, the lasted boot or shoe is placed upon the jack and is then brought into operative relation with the heel upon the nail block. Thereafter the machine is started, and nails 105 are driven from said block into the heel and

heel seat of the shoe to secure them together.

In the illustrated embodiment of the invention the jack 2 is pivotally mounted upon a transverse pin 4 which projects from a lug formed on a sliding plate 6. The plate 6 is mounted to slide from front to rear in guideways 8 formed on the lower end of a post 10 mounted for vertical movement in the machine frame 12. The sliding plate 6 is kept in the guideways by gibbs 9 which are secured to flanges formed on the lower end of the post 10.

The jack 2 hangs downwardly from its pivot 4 and is adapted to be moved from the position shown in Fig. 1 toward the front of the machine without angular movement, and then to be canted as shown in Fig. 2 to receive the work. The position to which the jack 2 can be canted forwardly is determined by a stop 16 upon it which engages the sliding plate 6 when the jack is canted. A catch member 18 is mounted in the stop 16 and is arranged to be received in an opening 20 in the plate 6 where it is engaged by a spring plunger 22. The catch 18 and the spring plunger associated therewith serve to hold the jack in its canted position.

The jack is prevented from being swung in an opposite direction or rearwardly by a projection 24 on the jack that contacts with a corresponding projection 26 on the sliding plate 6 when the jack is in its vertical and rearmost position.

Secured by screws 28 to the jack 2 is an arm 30 which projects rearwardly at substantially right angles to the jack, the jack and arm 30 constituting, in fact, a bell crank lever. Adjacent to the rear end of the arm 30 there is provided a cam roller 32 which is received in a slot 34 formed in a plate 36. The plate 36 is secured to or formed as a part of one of the gibbs 9 before-mentioned in order that the cam plate 36 may be held stationary while the arm 30 and the roller 32 are free to be moved with the jack 2 and sliding plates 6 forwardly and rearwardly, from and into operative position. The slot 34 in the plate 36 extends from its outer end horizontally at first and then downwardly along a curved path, the center of curvature of which being the axis of the jack, that is to say the pivot pin 4.

From the foregoing description it will be apparent that when the jack 2 is in its operative position it will be held rigidly against all tendency to cant by the engagement of the roller 32 with the horizontal walls of the straight part of the slot 34. When the jack is drawn forwardly with the sliding plate 6 the roller 32 will travel along the straight part of the slot 34 until it reaches the downwardly curved portion thereof. When the roller reaches this part of the slot the jack will be free to be swung

forwardly and canted into position to receive the boot or shoe, the roller 32 traveling along the curve while the jack turns about the pivot 4. The jack will then be held in its canted position by the plunger 22 and the catch member 18 until it is desired to return it to its operative position. This may be effected by pressing the jack rearwardly, the spring plunger 22 yielding to release the catch member.

By the construction and arrangement of the slot 34 the jack is free to be moved outwardly of the machine and canted for the removal and replacement of the work by a single pull upon the jack by the operator, and returned into operative position by a single continued push. Moreover, having been moved by the operator into one position or the other, the jack remains in such position as long as desired.

Having now described my invention, I claim as new and desire to secure by Letters Patent of the United States:—

1. A work support for shoe machinery, comprising a slide movable from front to rear in a substantially horizontal path, a jack pivotally mounted upon the slide, and means for automatically locking the jack against pivotal movement when the slide is moved to one limit of its path.

2. A work support for shoe machinery, comprising a slide movable in a substantially horizontal path, a jack pivotally mounted upon the slide to swing about an axis disposed adjacent to one surface of the slide, and means for automatically locking or unlocking the jack in respect to its swinging movement in accordance with the position of the slide in its path.

3. A work support for shoe machinery, comprising a slide movable from front to rear, a jack pivotally suspended from the slide, and means limiting the jack to sliding movement while the slide is in one position and to swinging movement while the jack is in another position.

4. A work support for shoe machinery, comprising a jack mounted for bodily movement from front to rear and also for swinging movement, and means for preventing swinging movement of the jack while the jack is in its rearmost position, said means being constructed and arranged to leave the jack free to swing while in its forward position.

5. A work support for shoe machinery, comprising a carrier member movable from front to rear, a jack pivotally mounted on the carrier member and having a rearwardly extending arm, a cam follower upon said arm, and a member located at the rear of the jack and having a cam shaped to control the movement of the jack through the cam follower.

6. A work support for shoe machinery,

75

85

95

100

110

120

130

comprising a carrier member movable from front to rear, a jack pivotally suspended from the carrier, a cam disposed at one side of the jack and having connections therewith for controlling the swinging of the jack, and a stop located between said controlling cam and the axis of the jack for determining the operative position of the jack.

10 7. A work support for shoe machinery, comprising a post having formed at one end guideways which extend from front to rear, a plate having a cam slot, and a jack pivotally mounted in front of the plate and controlled in its swinging movement in accordance with its distance from said slot.

8. Shoe supporting mechanism for a heeling machine, comprising a jack pivotally mounted at its upper end to swing in a plane extending longitudinally of a shoe supported thereon, a sliding carrier for the jack, means for yieldingly holding the jack with its shoe receiving end elevated, said carrier and slide being so constructed and arranged that pressure against the shoe will first swing the jack downwardly and then slide it rearwardly, and means for positively controlling the movement of the jack at all points in its path.

30 9. A work support for shoe machinery, comprising a pivoted and slidable jack for supporting a shoe and a stationary member located behind and above a shoe on the jack, one of said elements having a slot with straight and curved portions and the other a runner for limiting the movement of the

jack first to sliding and then to swinging movements.

10. A work support for shoe machinery, comprising a sliding plate having a jack pivotally mounted thereon, stops for determining the operative position of the jack, a catch for temporarily holding the jack in its work receiving position, and means for controlling the movement of the jack between said two positions.

11. A work support for shoe machinery, comprising a jack carrying member arranged for vertical movement, a slide transversely movable upon said member, a jack pivotally mounted upon the slide, and means for locking the jack against pivotal movement when the slide is moved to one limit of its path.

12. A work support for shoe machinery, comprising a slide, a jack hinged to the slide and a cam plate, said cam plate having a straight portion and a portion curved on an arc described about the axis of the jack when the jack is moved to one limit of its path and a cam follower connected to the jack and controlling the movement thereof by engagement with the surfaces of the cam.

In testimony whereof I have signed my name to this specification in the presence of two subscribing witnesses.

JOSEPH GOULDBOURN.
